HINGED BUTT JOINT

Angelo A. Rizzuto, Box 325, General Post Office,
New York, N.Y.

Filed Feb. 19, 1959, Ser. No. 794,465

3 Claims. (Cl. 287—99)

This invention relates to improvements in butt joints for flanged structural members such as I beams, T beams, and channel irons, and more particularly to an improvement in a fish joint construction wherein structural members are hingedly connected and thereby permit the use of a slidable fishplate, and this application further relates to my copending application, Serial No. 661,644, filed May 27, 1957.

An object of the present invention is to provide a simple and practical means whereby hingedly connected structural members may be butt-jointed or folded as desired or required.

Another object is to provide a simple manually-operated device which will butt-joint hingedly connected structural members without the use of or need for special tools or equipment.

A further object is to provide a simple and practical device which can be adapted to lock in extended position hingedly connected structural members each having a flat central web portion.

In the accompanying drawing forming a part hereof:

Fig. 1 is a perspective view of the preferred embodiment of the invention illustrating a butt joint formed by means of a slotted slidable plate which is retained securely in a fixed position by a pronged locking pin.

Fig. 2 is a side view of hingedly connected abutting structural members illustrating the modifications and guiding attachments required to render the invention operative.

Fig. 3 is a face view of the slotted plate which forms the butt joint.

Fig. 4 is a perspective view of the pronged locking pin which serves as a fastening means.

Fig. 5 is a top view of the illustration in Fig. 1 with the hinge and guiding attachments omitted to illustrate clearly the butt joint formed by the invention, the various parts of which are indicated by dotted lines.

Fig. 6 is a side view of a pair of bolts provided with thumbscrews which may be substituted for lugs.

Fig. 7 is a side view of a double-shafted pin which is threaded and provided with thumbscrews and which may be substituted for the pronged locking pin.

Fig. 8 is a side view of the illustration in Fig. 1 showing how the butt joint is broken by a retraction of the slotted plate and the consequent folding of the structural members.

As seen in the drawing, the invention is an improved fishplate which is slidable and modified to serve substantially the same purpose as an ordinary fishplate without the permanent fastening means which the ordinary or conventional fishplate usually requires. By means of the invention, rigid hingedly connected structural members which are required to be maintained in alignment only temporarily, such as side rail sections of a foldable ladder, can be made useful whenever and wherever desired without the need for any complicated and time-consuming mechanical operations.

The invention consists of a pair of structural members

2

1 and 2 having upper and lower flanges and a web portion such as I beams which are disposed in alignment and connected by a hinge 19, an elongated slotted plate 4, a pronged locking pin 9, and two pairs of angle bars 12. The web portion 3 of one structural member 1 is provided with a pair of diametrically positioned lugs 6 and the web portion 3 of the other structural member 2 is provided with a closed diametrically positioned longitudinal slot 7 and perforations 15 at each end of the slot 7 in a spaced relation thereto. Attached to the upper and lower flanges of both structural members 1 and 2 are angle bars 12 which serve as retaining as well as guiding members. The plate 4, as seen in Fig. 3, has an open longitudinal slot 5 at one end and in the solid portion thereof is provided with perforations 13 and 14 one thereof being centrally positioned and the others being positioned in spaced relation thereto respectively. The locking pin 9 is provided with a head 8 having prongs 11 extending therefrom which are positioned in a spaced relation to the pin 9, and an end piece 10 which serves as a retaining means for the pin 9.

In operation, the plate 4 is slidably disposed on the web portion 3 of the structural members 1 and 2 and between the upper and lower angle bars 12 the plate 4 being secured against lateral displacement thereof and being guided in a reciprocal sliding movement by said bars 12. The perforations 13 and 14 in the plate 4 are adapted to register with the slot 7 and the perforations 15 in the web portion of the structural member 2 respectively. This is necessary to permit the pronged locking pin 9 to be fitted onto the plate 4 so that the pin 9 engages in the centrally formed perforation 13 in the plate 4 and also in the slot 7, and the prongs 11 engage in the perforations 14 in the plate and also in the perforations 15 when the pin 9 is in either an operative position, as in Fig. 1, or in an inoperative position, as in Fig. 8. The pin 9 is slidably disposed within the perforation 13 and the slot 7 permanently while the prongs 11 are slidably disposed within the perforations 14 permanently and are engageable in and slidably disposed in the perforations 15 only when the plate 4 is in one or the other of the positions referred to. The end piece 10 prevents a disengagement of the pin 9 from the plate 4 when the pin is retracted to permit the plate to assume one position or another. In an operative position the plate 4 is locked against any movement thereof by the pin 9 and maintains the structural members 1 and 2 rigidly in alignment by engaging the lugs 6 in the open slot 5 thereof.

If desired or required, headed bolts 16 provided with thumbscrews 17 may be substituted for the lugs 6 and a double-shafted pin 18 also provided with thumbscrews 17 may be substituted for the pronged pin 9, in which case the perforations 14 and 15 would be useless and an additional perforation 13 in the plate 4 would be required to accommodate the extra pin shaft in the double-shafted pin 18. Such a combination would serve to impart to the invention the function of the ordinary permanently attached fishplate without the disadvantage of requiring any time-consuming operation to obtain substantially the same results. However, this combination obviously does not permit the use of the invention with the same speed as the preferred form. In any case, the invention in one form or another is complete within itself and does not require the use of tools or accessories of any sort.

Inasmuch as the invention illustrated and described herein is clearly capable of numerous modifications, it should be understood that changes may be made in the form and structural details of the invention without departing from the spirit and scope thereof as hereinafter claimed.

What is claimed is:

1. A hinged butt joint construction comprising, in combination, first and second structural members each having a central web portion with the central web portion of said first structural member containing a longitudinal slot, a hinge connecting adjacent ends of said structural members, a plate slidably attached to the web portion of said first structural member and having a slot entering the end of said plate facing in the same direction as the end of said first structural member, means projecting from the web portion of said second structural member to engage the slot in said plate when said structural members are unfolded into an extended relation and said plate is then slid outwards alongside the web portion of said second structural member, and locking means extending through said plate and the slot in the web portion of said first structural member, said locking means limiting the movement of said plate from an extended to a retracted position alongside said first structural member and said locking means selectively securing said plate to said first structural member in extended and retracted positions.

2. The combination according to claim 1 wherein said means projecting from the web portion of said second structural member comprises at least two spaced apart lugs.

3. The combination according to claim 2 wherein said locking means comprises a pin extending through the slot in said first structural member and through an aperture in said plate, said pin having an enlarged end piece, a flat head on said pin disposed adjacent to said plate, and prongs extending from said head into corresponding apertures in said plate so that said pin and said head may be moved to engage said prongs with one of two sets of corresponding apertures in the web portion of said first structural member to selectively lock said plate in an extended or a retracted position.
